CLAIM

The ornamental design for an electronic taper candle having a flame-shaped element illuminated on two sides thereof, as shown and described.

DESCRIPTION

FIG. 1 is an isometric view of the electronic taper candle; FIG. 2 is a front view of the electronic taper candle of FIG. 1, illustrating the illuminated area on one side of the flame-shaped element;

FIG. 3 is a rear view of the electronic taper candle of FIG. 1, illustrating the illuminated area on the opposite side of the flame-shaped element;

FIG. 4 is a left side view of the electronic taper candle of FIG. 1;

FIG. 5 is a right side view of the electronic taper candle of FIG. 1;

FIG. 6 is a top view of the electronic taper candle of FIG. 1; and,

FIG. 7 is a bottom view of the electronic taper candle of FIG. 1.

The broken lines of FIGS. 1-7 are provided for purposes of illustration and form no part of the claimed design of the present application.

1 Claim, 4 Drawing Sheets
